 one-third to Gertrude E. Byer

Application March 11, 1937, Serial No. 130,250

6 Claims. (Cl. 46—19)

This invention relates to building structures, such as houses and the like, and has particular reference to a novel building structure which may be readily assembled and disassembled and which when assembled is strong and durable.

It is well known that a relatively large item of expense in the construction of buildings is the manufacture and assembly of special parts which must be cut to fit the particular plans of the building and assembled piece by piece usually at the building site. In order to lower the cost of construction, it has been proposed heretofore to construct buildings of standard sections or units which may be made at the factory with the advantages of mass production. The sections thus made are assembled in the desired combination at the building site. One of the principal problems in assembling the structure is the joining of the various wall panels which comprise an important part of the assembly. It is often necessary to employ several panel sections to make a single wall or partition, and in such cases the adjacent sections must be joined in such a manner as to provide a tight closure and maintain the sections in position at all times. Also, a suitable joint must be made at each intersection of walls and at the junction of dividing partitions with walls or other partitions.

One method employed heretofore for joining the panel sections requires overlapping adjacent panel sections where aligned sections are to be joined and butting the edge of a section against the surface of another section where intersecting sections are to be joined. This method is objectionable for the reason that the overlapping portions are unsightly and destroy the smooth appearance of the assembly and the butting portions do not afford a secure joint. Another method of joining the sections is to mount uprights on the floor or base of the structure between the adjoining edges of adjacent sections and connect the sections along their edges to the uprights. The uprights, however, present an unsightly appearance and require careful installation to mount them accurately between the adjoining edges of the panel sections.

The present invention is directed to the provision of a novel building structure of the prefabricated section type in which the panel sections may be joined quickly and easily along their adjacent edges without overlapping or butting and without reference to connecting posts or uprights mounted in the floor. In addition, the sections of the new structure may be readily disassembled after they are joined, and accord-

ingly the structure is particularly suited for manufacture on a small scale for use as a toy. Preferably, the structure of the present invention also includes novel means for mounting the wall sections on a base or the like.

A structure made in accordance with our invention comprises a base or floor section and a plurality of panel sections mounted on the base and extending upwardly therefrom. The panels are arranged on the base in accordance with a predetermined plan to form the side walls and partitions of the structure and are preferably removable from the base. The panels of each wall and partition are positioned in close relation with their adjacent edges substantially contacting, and each panel is formed with grooves along its lateral edges whereby the grooves in adjacent edges form a slot or passage in the wall or partition extending substantially from top to bottom. To join adjacent panels, we provide means disposed in the slots thus formed for holding the panels securely in alignment and effecting a tight closure between them. The joints may take various forms. One form of joint which we employ comprises a spline inserted in the adjacent grooves forming the slot. The spline is preferably removable from the slot, although if desired it may be permanently cemented therein. Another form of joint which may be used comprises a tie rod extending through the slot and provided at one end with a connecting member which engages the adjoining top or bottom edges of adjacent panels so as to lock the panels together. At its opposite end the tie rod may be provided with means for tightening the rod and thereby drawing the connecting member more firmly against the panels. Various other forms of joints may be inserted in the slots to effect the desired connections, but it will be apparent that whatever form the joint may take it is completely concealed in the slot so that the aligned panels may be connected in contacting relation without exposing the joining means.

At the intersections of walls and partitions, the panels are connected by connecting members which comprise an elongated member provided with tongues extending from lateral faces thereof in different directions. Where two walls or partitions intersect to form a corner, the joining member is formed with two tongues extending at right angles and received in the grooves in the adjacent lateral edges of the intersecting panels. At the intersection of a partition and a wall, the joining member has three

tongues, two of which are oppositely disposed and received in the grooves of the aligned panels forming the intersected wall, the third tongue extending at right angles to the first two and received in the groove in the adjacent edge of the intersecting panel. Where there is a four corner intersection of partitions, the joining member is provided with four tongues received in the grooves formed in the adjacent edges of the four intersecting panels.

With this construction, the panels are held securely together along their adjacent edges after they are mounted on the base, and the means for effecting their connection do not detract from the appearance of the structure. The joining means for aligned panels are substantially concealed and those for intersecting panels may be constructed so that the exposed faces thereof lie flush with the surfaces of the adjacent walls. Since the means for joining the adjacent edges of the panels may be readily removed from the grooves in the panels, the structure may be readily disassembled.

In the preferred form of the structure, the panels are formed with grooves along their bottom edges as well as their lateral edges and are held in position on the base by splines secured to the base and received in the bottom grooves of the panels.

For a better understanding of the invention reference may be had to the accompanying drawings, in which:

Fig. 1 is a perspective view of one form of the new structure partially assembled;

Fig. 2 is a perspective view of one corner of the base showing two aligned panels mounted thereon and joined to each other;

Fig. 3 is a plan view of the unit employed for connecting two intersecting panels to form a corner;

Fig. 4 is a similar view of a connecting unit employed at an intersection of a partition with a wall or other partition;

Fig. 5 is a similar view of a connecting unit used at a four-cornered intersection of panels;

Fig. 6 is a perspective view of one corner of the base showing modified means for mounting panels on the base and joining adjacent panels;

Figs. 7 and 8 are perspective views of the two forms of connectors shown in Fig. 6 for mounting the panels on the base;

Fig. 9 is a view in perspective of the tie rod for joining adjacent panels;

Fig. 10 is a view in section showing the tie rod applied to adjacent panels mounted on the base;

Fig. 11 is a perspective view of one corner of the base showing another form of connector for mounting the panels on the base.

We have illustrated in the drawings a building structure in the form of a toy, although it will be understood that the principles of our invention are equally applicable to full scale building construction.

Referring to Fig. 1 of the drawings, the structure there shown comprises a rectangular base 20, preferably of wood, provided on its upper surface with guide lines 21 extending longitudinally and transversely thereof at right angles. The lines 21 are preferably arranged in pairs with the lines of each pair extending parallel in closely spaced relation. Mounted on the base 20 and extending vertically therefrom are a plurality of panels 22 of uniform width and height, preferably of the same material as the base. The

panels 22 are of various forms, some of the panels being solid, others being formed with doorways 22a and others with windows 22b. Each of the panels 22 is formed with a groove, not shown, extending along the bottom edge thereof. As shown particularly in Fig. 2, the panels 22 are held in position on the base by splines 23 which fit tightly into the bottom grooves of the panels, the splines being attached to the base by any suitable means, such as brads 24. If desired, the splines may be cemented into the bottom grooves of the panels whereby the connection of the panels to the base is permanent. Preferably, however, the panels are secured to the base only by the spline and groove connection, whereby they are removable from the base. The splines 23 are attached to the base in accordance with a predetermined plan between selected pairs of the guide lines 21, so that when the panels 22 are mounted on the base as described they will form the partitions and walls of the building. Panels 25 of substantially less width than the standard panels 22, but otherwise similar thereto, are preferably provided to complete a wall or partition where it is desired to space a doorway or window panel from another panel of the wall or from an intersecting wall a distance less than the width of a standard panel.

Each of the panels 22 is formed with grooves 26 similar to the bottom groove therein but extending along the lateral edges of the panel. It will be observed that the grooves 26 in the lateral edges of adjacent panels cooperate to form a slot extending from top to bottom of the wall or partition. In order to join the adjacent edges of aligned panels, we insert in the slots thus formed a spline 27 of wood or the like. The spline is adapted to fit tightly in the slot and extends from the top to the bottom thereof so that the panels are held securely against relative out-of-line movement. The splines 27 are preferably removable from the slots formed by grooves 26, but if desired they may be cemented therein so as to make the joints permanent.

At the corners formed by intersecting walls and partitions, the panels 22 are joined by connecting members 28. Each of the members 28 comprises an elongated piece, preferably of wood, having a generally square cross section so that it has four flat lateral faces. As shown particularly in Fig. 3, two adjoining lateral faces of the connecting member have tongues 28' extending outwardly therefrom, and these tongues extend substantially the length of the member. It will be observed that the distance between opposite faces of the member 28 is substantially equal to the thickness of the panels 22. The members 28 are disposed at the corners formed by intersecting walls or partitions with the tongues 28' extending into the grooves 26 in the adjacent edges of the panels forming the corners.

Where the partitions of the structure intersect a wall thereof or another partition, the panels are joined by a connecting member 29 of the form shown in cross section in Fig. 4. The connecting members 29 are similar to connecting members 28 except that each of them has tongues 29' extending from three of the four lateral faces thereof. As shown particularly in Fig. 4, the connecting member 29 is disposed at the intersection of the panels 22 with the oppositely disposed tongues 29' extending into the grooves 26 in the two aligned panels, and the third tongue 29' extending at right angles to the other tongues into

the groove 26 formed in the adjacent edge of the intersecting panel 22.

If it is desired to join the panels forming a four-corner intersection (not shown), we employ 5 a connecting member 31 of the form shown in section in Fig. 5. As there shown, the connector 31 is similar in form to the connector 29 except that it is provided with a tongue 31' on each of the four faces thereof. The connector 31 is 10 positioned at the intersection of the panels with the tongues 31' extending into the grooves 26 in the adjacent edges of the intersecting panels, as shown in Fig. 5.

It will be apparent that with this construction 15 the splines 23 may be laid out on the base in any configuration and the panels 22 readily mounted thereon and joined together at their adjacent edges to form a building of the desired architectural design. The splines 21 provide strong joints 20 between the lateral edges of aligned panels and together with the splines 23 maintain the panels firmly in position at all times. Since the splines 23 and 21 are completely concealed in the panel 25 grooves, the joints present a smooth and attractive appearance. The connecting members 27 and 29 at the intersections of the walls and partitions have their outer faces flush with the surfaces of the walls and partitions, and accordingly do not destroy the smooth surfaces of the structure. The spline-and-groove and tongue-and-groove 30 connections permit the structure to be quickly and easily disassembled, as will be readily apparent. Any one of the panels 22 may be easily withdrawn vertically from its position between 35 adjacent panels by reason of the spline-and-groove connections, and removal of the panels in this manner greatly facilitates disassembly of the structure.

Instead of assembling the panels 22 on the base 40 by splines of the form shown in Figs. 1 and 2, the panels may be assembled by the connections shown in Fig. 6. As there shown, the panels 22 forming one wall are held in position on the base 20 by an elongated spline 45. The spline 45, as 45 shown particularly in Fig. 7, has a cross section of an inverted U-shape, the top thereof being flat, and is provided with prongs 45' projecting downwardly from the lower edges of the sides at spaced points therealong. The spline 45 is preferably made of metal, the prongs 45' being integral therewith, and may be conveniently made by a stamping operation. In mounting the spline 45 on the base, it is placed in the desired position 50 between guide lines 21 with the prongs 45' resting on the base. The top of the spline is then 55 pressed downwardly so as to embed the prongs in the base and thereby secure the base against displacement. The panels 22 are then mounted on the base with the splines 45 extending into 60 the bottom grooves therein. Alternatively, the panels forming one wall may be held in position on the base by a spline 46 of the form shown in Fig. 8. The spline 46 is generally U-shaped in section, the base thereof being flat, and is formed 65 with openings 46' spaced along the base. Preferably, the spline 46 is made of metal. The spline is mounted on the base in the desired position with the legs thereof resting on the base, as shown in Fig. 6, and is held against displacement on the 70 base by brads (not shown) which are inserted in opening 46' and driven into the base. The panels 22 are positioned on the base with the bottom grooves therein coinciding with spline 46, the base of the groove resting on the top of the spline. 75 The adjacent edges of the panels 22 may be

joined together by the connection shown in detail in Figs. 9 and 10. As shown particularly in Fig. 10, the connection comprises a hollow spline 47 of rectangular section which extends vertically through the slot formed by the grooves in the 5 adjacent edges of the panels. The spline 47 is preferably of metal and is formed to fit tightly in the slot. Extending through the spline 47 from top to bottom is a tie rod 48 which may be made of wire or the like. At its upper end, the tie rod 10 48 is suitably connected to a horizontal plate 49 which rests on the adjoining upper edges of panels 22. The plate 49 is likewise of metal and is stamped out to form two downwardly extending prongs 50, one of which is embedded in the 15 panel 22 on one side of spline 47 and the other of which is embedded in the panel on the opposite side of the spline. At its lower end, the tie rod 48 extends through an opening 51 drilled in the base and is provided with a headed member 52 20 threaded thereon. The opening 51 at its lower end opens into a circular recess 53 formed in the bottom of the base, and the head of the member 52 is disposed in the recess in engagement with the base, the shank of the member extending into 25 the opening 51.

In assembling the joint shown in Fig. 10, the panels 22 are first mounted on the base with the hollow spline 47 extending through the slot formed by their adjacent grooves 26. The tie rod 30 48 is then passed through the spline from the top and through opening 51 which may be drilled in the base in the desired location, and the prongs 50 of the plate 49 are firmly embedded in the top 35 of the adjacent panels. Thereafter, the headed member 52 is threaded onto the lower end of the tie rod and screwed tightly against the base in the recess 53, thereby drawing the plate 49 at the other end of the tie rod downwardly against the adjoining upper edges of the panels. 40

A modified form of joint for mounting the panels 22 on a base or floor section is shown in Fig. 11. As there shown, the base 20 is formed on its upper surface with slots 55 extending longitudinally and transversely thereof. The 45 slots 55 are of the same dimensions as the slots formed in the bottom edges of the panels 22. The panels are attached to the base by means of splines 56 which are received in the slots 55 50 in the base and extend upwardly into the slots 55 formed in the bottom edges of the panels. The splines 56 are of considerably greater height than the spline 23 shown in Figs. 1 and 2, so that when it is inserted in one of the slots 55, substantially one-half of the spline projects above 55 the upper surface of the base into the cooperating slots in the bottom of the panels.

It will be apparent that the new building construction may be used to particular advantage as a toy, since the parts thereof may be assembled quickly and easily into attractive structures of various architectural designs and may be readily disassembled. The structure, when assembled 60 presents a smooth and attractive appearance, the joints either being completely concealed or else having their exposed surfaces flush with the adjacent surfaces of the walls and partitions. Accordingly, the structure has the appearance of a small scale building accurately proportioned 65 even at the joints. 70

We claim:

1. A building structure comprising side walls, at least one of which is formed by a plurality of aligned panels having grooves in adjacent edges thereof, the grooves in adjacent edges of 75

- adjoining panels cooperating to form a slot, a tie rod extending through the slot and held at one end against relative longitudinal movement in the slot, and a member connected to the opposite end of the tie rod engaging adjoining edges of the adjacent panels to hold the panels in a fixed relationship.
2. A building structure comprising side walls, at least one of which is formed by a plurality of aligned panels having grooves in adjacent edges thereof, the grooves in adjacent edges of adjoining panels cooperating to form a slot, a tie rod extending through the slot, a member connected to one end of the rod and engaging adjoining edges of the adjacent panels to hold the panels in a fixed relation, means for securing the opposite end of the tie rod to maintain tension therein, and means for varying the tension in the rod.
3. A building structure comprising side walls, at least one of which is formed by a plurality of aligned panels having grooves in adjacent edges thereof, the grooves in adjacent edges of adjoining panels cooperating to form a slot, a tie rod extending through the slot and held at one end against relative longitudinal movement in the slot, and a member connected to the opposite end of the tie rod provided with a pair of projections, one projection penetrating the panel on one side of the slot and the other penetrating the panel on the opposite side of the slot.
4. A building structure comprising side walls, at least one of which is formed by a plurality of aligned panels having grooves in adjacent edges thereof, the grooves in adjacent edges of adjoining panels cooperating to form a slot, a spline disposed in said slot and having a longitudinal passage therein, a tie rod extending through said passage and held at one end against relative longitudinal movement in the slot, and a member connected to the opposite end of the tie rod engaging adjoining edges of the adjacent panels to hold the panels in a fixed relationship.
5. A building structure comprising a base having a plurality of openings therethrough, a plurality of aligned panels supported on the base, each panel having grooves in the lateral edges thereof, the grooves in adjacent edges of the panels cooperating to form a slot, a tie rod extending through said slot and through one of said openings in the base, a member connected to one end of the tie rod engaging adjoining edges of the adjacent panels to hold the panels in a fixed relationship, and a headed member threaded on the opposite end of the tie rod and adapted to be screwed against the bottom of the base to apply tension to the rod.
6. A building structure comprising side walls, at least one of which includes a pair of aligned panels arranged in substantially edge to edge relation, said panels including a vertical slot, a tie rod extending through the slot, means at one end of the rod for holding the rod against longitudinal movement in the slot, and a member on the opposite end of the tie rod generally perpendicular thereto and provided with a pair of spaced projections generally parallel to the rod, one of the projections extending into one of the panels and the other projection extending into the adjacent panel to hold the panels together.

RAYMOND V. PARSONS. 35
